UNITED STATES PATENT OFFICE

2,078,639

SMOKEHOUSE

Fred E. Rohrmann, Milwaukee, Wis.

Application October 12, 1934, Serial No. 748,061

2 Claims. (Cl. 99—259)

This invention relates to smokehouses and more particularly to a smokehouse having a smoke circulatory system.

An object of the invention is to provide a device of the type having means for equalizing pressure in the smokehouse.

Another object of the invention is to provide a circulatory system which will make constant the heat and smoke in the unit.

10 A further object is to provide means for thoroughly mixing the heat and smoke adjacent its origin with the return smoke.

Other and further objects of the invention will appear as the description proceeds; reference being had to the accompanying drawing, in which:—

Fig. 1 is a side view in section of a device embodying my invention.

Fig. 2 is a plan view partly in elevation and partly in section showing return and terminal pipes.

Fig. 3 is a rear view of the device partly in section and partly in elevation showing the smoke flue, blower, return and terminal pipes.

25 Referring more particularly to the drawing, the numeral 10 refers to the fire box of the device. The smoking compartment is disposed at 11 thereof, and opens into the flues 12 and 13. A side flue 14 leads to the blower 15 and return pipe 16, which is supported at its lower end, in 30 the rear wall, 17, of the smokehouse.

Pipe 16 terminates in a transversely disposed terminal pipe 18, having the damper box 19 in 35 which is the sliding damper 20. The upper portions of the terminal pipe 18 are cut out at 21, and are covered by the sliding cover 22, which has registering cutout portions at 23. The terminal pipe 18 supports a longitudinal axle 24, on which 40 are mounted the fans 25, which may be secured by this means or held by hangers directly within or under the openings at 21 of pipe 18. Hand levers 26 and 27 control the sliding top cover and the damper, respectively.

In operation, the food products to be smoked 45 are suspended in the compartment 11, where they will be subjected to the smoke issuing from the fire box 10. If the dampers 20 are open, the smoke will leave compartment 11 by means of the flues 12 and 13. By opening the damper 19, the

blower 15 will draw the smoke by means of flue 14 through said blower into the return pipe 16 and the terminal pipe 18. The operator, by opening the damper 20, may release the smoke from the return pipe into the fire-box 10, thus utilizing 5 combustible materials, which may remain in the return smoke, and re-heating it for re-circulation. If it is not desired to re-heat or burn the smoke, it may be released thru the openings at 21, by moving the cover 23, whereupon the free rotating 10 fans 25 will tend to mix the original smoke with the return smoke.

It will be understood that the device is capable of many modifications in structure and design, without departing from the spirit of the invention, 15 all within the scope of the appended claims. Having thus described my invention, what I claim and desire to secure by Letters Patent of the United States, is:—

1. In a device of the class described, a firebox, 20 a smoking compartment above said firebox having ventilating projections at the top thereof, a return pipe connected with said ventilating means, a transverse terminal pipe connected with said return pipe at the lower end thereof having a 25 plurality of vents in the upper and lower sides thereof adapted to diffuse smoke upwardly through the smoking compartment, the lower vents being adjacent to the firebox and adapted to feed smoke to the fire for reburning thereof, 30 and closure means operable exteriorly of the compartment for opening and closing the lower and upper vents respectively.

2. In a device of the class described, a firebox, 35 a smoking compartment above said firebox having ventilating projections at the top thereof, a return pipe connected with said ventilating means, a transverse terminal pipe connected with said return pipe at the lower end thereof having a 40 plurality of vents in the upper and lower sides thereof adapted to diffuse smoke upwardly through the smoking compartment and downwardly into the firebox for reburning thereof, free rotating agitating means adjacent to on a plane with and disposed inwardly of the plane of the 45 upper vents, and closure means operable exteriorly of the compartment for opening and closing the lower and upper vents respectively.

FRED E. ROHRMANN.
